LOCOMOTIVE BOILER

Filed Aug. 17, 1929

Inventor:
Bert E. Larson
By Arthur J. Wilcox
Attorney

UNITED STATES PATENT OFFICE

BERT E. LARSON, OF PARK RIDGE, ILLINOIS, ASSIGNOR TO LOCOMOTIVE FIREBOX COMPANY, OF CHICAGO, ILLINOIS, A CORPORATION OF DELAWARE

LOCOMOTIVE BOILER

Application filed August 17, 1929. Serial No. 386,660.

This invention relates to improvements in locomotive boilers and it consists of the matters hereinafter described and more particularly pointed out in the appended claims.

The primary object of the invention is to provide in a thermic siphon equipped locomotive boiler, a novel connection for the inlet neck of the siphons, with a point forward of the front water leg, which connection is located outside of the boiler shell where it is easy for access for cleaning and inspection.

Another object of the invention is to provide a well on the outside of a portion of the boiler shell forward of the front water leg and in communication with the interior of said shell with which the inlet necks of the siphons in the fire and combustion chambers respectively may be readily connected in a manner permitting movement of said siphons under the action of temperature changes, without leakage.

These objects of the invention, as well as others together with the many advantages thereof will more fully appear as I proceed with my specification.

In the drawing:—

Fig. 1 is a longitudinal vertical sectional view through the firebox end of a locomotive boiler embodying my invention.

Fig. 2 is a fragmentary detail sectional view of parts shown in the lower right hand corner of Fig. 1 on an enlarged scale.

Referring now in detail to that embodiment of the invention illustrated in the accompanying drawing, the boiler includes a firebox comprising a flue sheet 1, an inner rear sheet 2 and a crown sheet 3 extending therebetween. 5 indicates one of the side sheets of the firebox which includes a fire chamber 6 and a combustion chamber 7 forward of the same. The bottom 8 of the combustion chamber is made as a continuation of the inner front throat sheet 9 of the firebox.

10 indicates the shell of the boiler, 11 the outer rear sheet therefor and 12 indicates the outer front throat sheet of the boiler. Several of the sheets mentioned provide the front water leg or throat 13, the rear water

leg 14 and side water legs (not shown) all in communication with the boiler water space of the boiler and closed at their bottom end by the mud ring 15. The open bottom of the fire chamber 6 has the usual grate as indicated by the dotted line 16 and in the flue sheet 1 are secured the usual flues 1^a through which the products of combustion pass on their way to the usual smoke box at the front end of the boiler. The construction described may be taken as typical of locomotive boilers having fireboxes of the combustion chamber type.

To increase the efficiency of boilers having fireboxes of this type, auxiliary water steaming and circulating elements are employed in both the fire chamber and in the combustion chamber. Such elements usually are what have now become known as the Nicholson thermic siphons and each comprises a flat hollow body disposed longitudinally in the firebox and opening at one end, through the crown sheet and terminating at the other end in a tubular inlet neck. Heretofore the neck of the siphon in the fire chamber opened thru and was fixed in the inner throat sheet 9 and the neck of the siphon in the combustion chamber opened through and was fixed in the bottom wall 8 of the combustion chamber.

As the flat hollow body of the siphons present a considerable heating surface area to the products of combustion, it is apparent that a movement of the elements develops under change of temperature. Heretofore, it has been attempted to accommodate such movement by forming annularly corrugated flexible diaphragm parts in the front throat sheet 9 and bottom wall 8 of the combustion chamber respectively but such parts do not permit the degree of flexibility or accessibility desired for cleaning and inspection purpose.

In Fig. 1 is illustrated in side elevation two of such siphons each indicated as a whole by the numerals 17 and 18 respectively, with the former disposed in the fire chamber and with the latter disposed in the combustion chamber. The number of siphons of course is dependent upon the size

of the firebox and in some instances there are a plurality of such siphons in one or the other of said chambers. As shown herein for the sake of simplicity and convenience only one siphon is shown in each chamber. The siphon 17 includes a flat hollow, stay-bolted body 17^a which is fixed in the rear part of the crown sheet 3 and opens therethrough, and a tubular inlet neck 17^b disposed at substantially a right angle to the plane of the throat sheets 9 and 12 with which it is associated. The siphon 18 includes a flat hollow staybolted body 18^a which is fixed in the front part of the crown sheet 3 and opens therethrough, and a tubular inlet neck 18^b the bottom end of which is disposed at substantially a right angle to the plane of the bottom of the shell 10 and bottom wall 8 of the combustion chamber. Secured to the shell 10 in the plane of the siphon neck 18^a is a longitudinally extending, cup shaped well member 20. Said member includes a bottom wall 21 and side and end walls 22 and 23 respectively which are flanged at their top ends to fit and be tightly secured to the outer cylindrical surface of said shell as by the rivets as shown. In said shell are openings 10^a whereby communication is established between said shell and well. The shell includes a rearwardly facing tubular extension 24, the purpose of which will soon appear. In said bottom wall 21 is provided an opening, which is normally closed by a removable cover plate 21^a having a washout plug 21^b therein. 25 indicates a sleeve extending through the front water leg 13 and fixed at its ends in the sheets 9 and 12 respectively. The bottom end of the tubular inlet neck 17^b of the siphon 17 extends into said sleeve without engagement therewith and is there connected by a coupling 26 with the rear end of an elbow fitting 27. The front end of said fitting is made spherical as at 28 to engage 40 against packing rings 29 in the rear end of the tubular extension 24 of the well number 20. A flanged nut 30 is screwed onto the rear end of said tubular extension and surrounds a part of said elbow and carries a washer 31 to engage the packing. Thus when the nut is screwed up tight, the packing is compressed upon the spherical end of the elbow to provide a flexible but tight ball joint or connection between the extension 24 45 and elbow 27.

A sleeve 32 is fixed at its ends in the shell 10 and bottom wall 8 of the combustion chamber and the bottom end of the inlet neck 18^b of the siphon 18 passes down thru the same to extend into the well 20 where it is provided with a fixed collar 33 of a metal unaffected by immersion in water.

Fixed to the bottom surface of the boiler shell 10 about the collar 33 is a plate 34 having a bottom opening recess 35 defined by a

depending annular flange 36 and an inwardly extending radial flange or shoulder 37. A pair of flat annular packing members 38 is disposed in said recess to engage against the shoulder 37 and to surround the collar 33 on the siphon neck 18^b. Surrounding each packing member is a contractile spring 39 which normally acts to contract the packing members into snug engagement upon said collar. 70

A helical expansion spring 40 engages at one end against the bottommost packing member 38 and engages at its other end upon the cover 21^a which is provided with lugs 21^c to prevent lateral movement of said spring. This last mentioned spring acts to hold the packing members snugly up against the annual shoulder 37. 75

Under temperature changes in the fire and combustion chambers, both siphons 17 and 18 will take on a movement and as both siphons are fixed or anchored at their outlet ends in the crown sheet, it is apparent that such movement will manifest itself at the bottom or inlet end of the siphon. 80

In the case of the siphon neck 18^b, the same will slide through the packing members 38—38 without leakage. As to the siphon or siphons 17, the movement of the neck will be manifested in the ball and socket joint before described. 85

With the structure described, it is apparent that the movements mentioned are accommodated by a structure disposed entirely outside the boiler shell and in a position easily accessible for inspection and repair. This structure may be applied to locomotives already in service with but little lay-up time and may also be installed in new ones during the manufacture thereof. 90

While in describing my invention I have referred in detail to the form, arrangement and construction of the various parts thereof, the same is to be considered merely as illustrative except as may be specifically set forth in the appended claims. 100

I claim as my invention:

1. A locomotive boiler having a firebox including a fire and a combustion chamber, a water circulating and steaming member in each chamber and each including an inlet end, with one of said inlet ends disposed at substantially a right angle to the other, means providing a well below the boiler and in communication therewith, means providing a slip joint connection for said inlet end of the member in the combustion chamber with said well and means providing a ball and socket joint connection for the inlet end of said member in the firebox with said well. 115

2. A locomotive boiler having a firebox including a fire and a combustion chamber, a siphon disposed in each chamber and each fixed at its outlet end in the crown 120 well. 125

130

sheet and each having a tubular inlet end, with one of said ends disposed in a plane at substantially a right angle to the other, a well below and in communication with said boiler and means providing a slip joint connecting the inlet end of the siphon in the combustion chamber with said well and means providing a ball and socket joint connecting the inlet end of the siphon in the fire chamber with said well.

10 3. A locomotive boiler having a firebox including a fire chamber and a combustion chamber, a flat hollow water steaming and circulating member in each chamber and each having an inlet neck at one end, means providing a well below the boiler and in communication therewith, and including a rearward tubular extension, the inlet neck of the member in said combustion chamber 15 extending into said well, means in said well and engaging the last mentioned inlet neck to provide a slip joint connection therewith, and a tubular element secured to the inlet neck of the member in the fire chamber and 20 having a ball and socket joint connection with said rearward tubular extension of said well providing means.

4. A locomotive boiler having a firebox including a fire chamber and a combustion 30 chamber, a flat hollow water steaming and circulating member in each chamber and each having an inlet neck at one end, the inlet neck of the member in the combustion chamber extending at substantially a right 35 angle to the inlet neck of the member in the fire chamber, means providing a well below and in communication with the boiler and into which well the inlet neck of the member in the combustion chamber extends and 40 which means includes a rearward tubular extension, and means providing a ball and socket connection for the inlet neck of the member in the fire chamber with said tubular extension of said well providing means.

45 In testimony whereof, I have hereunto set my hand, this 13th day of August, 1929.

BERT E. LARSON.
